UNITED STATES PATENT OFFICE

ROLLA M. HARRELL, OF MONROE CITY, INDIANA

TARGET

Application filed April 30, 1928. Serial No. 273,892.

The present invention relates to targets for small arm practice, such as rifles, pistols and the like and has for an important object to provide means for moving the target transversely with respect to the line of fire of the fire arms.

A further important object of the invention is to provide means for moving the target across the line of fire of the marksman and returning the target to its original position.

A further important object is to provide a target construction with means for moving the same in a manner for simulating the movement of an animal running along the ground or for simulating the flight of a bird.

An additional object is to provide a carrier for the target upon which the target may be removably mounted so as to provide means for replacing the target after the same has been mutilated by the shot from the fire arm.

A still further object is to provide a target construction of this character of a simple and practical nature, which may be easily and quickly secured in operative position with respect to a shooting gallery or other place at which the target practice is conducted, which is relatively inexpensive to manufacture and install in operative position and otherwise well adapted for the purposes for which the same is intended.

Other objects and advantages reside in the special construction, combination and arrangement of the various elements forming the invention as more fully hereinafter described and claimed, reference being had to the accompanying drawings forming part hereof, wherein like numerals refer to like parts throughout, and in which:

In the drawings:

Figure 1 is a top plan view showing a set of targets in operative position,

Figure 2 is a front elevational view thereof,

Figure 3 is a fragmentary vertical sectional view through one of the supporting posts for adjustably securing one end of the guide wire or cable on which the target is movably mounted,

Figure 4 is a similar view through the opposite supporting posts for the opposite end of the guide wire,

Figure 5 is a longitudinal sectional view through the wire tightening drum, and

Figure 6 is a transverse sectional view through one of the target carriers taken substantially along a line 6—6 of Figure 3.

Referring now to the drawing in detail, the invention includes the provision of a pair of spaced apart vertically extending supporting posts 5 arranged adjacent each side of the target range, each of said posts having openings 6 formed therein and within which opening is rotatably mounted a pulley wheel 7.

The openings 6 in the respective posts is disposed adjacent the lower end thereof and attached to the outer sides of the post adjacent such opening is a bracket 8 having a drum 9 mounted for rotation thereon and about which drum is extended one end of a wire cable 10.

A square shaft 11 extends longitudinally through the drum and outwardly at each end thereof, one end of the shaft having a knurled nut 12 fixedly secured thereto and the opposite end of the shaft threaded for receiving a wing nut 13.

The nuts 12 and 13 are adapted to be tightened against the opposite sides of the bracket 8 whereby to secure the drum against rotation. From the opening 6 of one of the posts, the wires 10 extend upwardly at an inclined angle toward the opposite post and through an opening 14 formed adjacent the upper end thereof and over a pulley wheel 15 rotatably mounted in such opening, the upper end of the wire indicated at 16 being then attached to a stationary object shown at 17 in Figure 2.

A carrier 18 is arranged on the wire for movement longitudinally thereof, said carrier being constructed of a pair of duplicate sections 19 secured together by a pair of bolts and nuts 20, the connected faces of said sections having a recess 21 formed therein cooperating with each other for receiving a set of pulley wheels 22 arranged in pairs in superimposed relation and mounted for rotation upon shaft 23 supported in the respective sections.

A pair of the pulley wheels is arranged ad-

jacent each end of the carrier and the recesses 21 formed in each section extend longitudinally throughout the carrier whereby to permit the insertion of the wire 10 therethrough between the pulley wheels of each pair.

In this manner the pulley wheels 22 support the carrier upon the wire in a manner to facilitate the movement thereof on the same. In one of the carrier sections 19 is attached a spring clip 24 by means of which a target 25 may be attached to the carrier for movement therewith.

To the end of the carrier disposed lowermost is a bumper 26, preferably constructed of rubber or similar resilient material and likewise having an opening extending longitudinally therethrough for receiving the wire 10.

The under side of the bumper is provided with a recess 27 having a metallic winding 28, said recess being adapted to receive a trigger 29 having one end thereof threadedly inserted in the post adjacent the lowermost opening 6 thereof and adjustably secured in position therein by means of a nut 30.

A coil spring 31 is secured to the inner face of the post against the opening 6 with the wire 10 extending longitudinally therethrough, the spring thus being interposed between the bumper 26 and the post. A coil spring 32 is also attached to the inner face of the opposite post adjacent the upper opening 14 thereof and likewise arranged with the wire 10 extending therethrough, the outer end of the spring having a bumper 33 attached thereto to receive the impact of the carrier as the same approaches the upper portion of the post.

The trigger 29 is adjusted so as to secure the carrier 18 against the spring 31 while in a compressed condition so that upon the releasing of the trigger the spring will be released thereby causing the carrier to move upwardly along the wire 10 in a direction toward the opposite post.

Upon striking the bumper 33 at the upper end of said post the spring 32 will become compressed and being free to expand will consequently return the carrier to its original position. As clearly illustrated in Figures 1 and 2 of the drawings any desired number of the target structures may be mounted at the sides of the target way and by providing posts 5 of a suitable play two or more sets of targets may be oppositely supported thereby.

The target may be assembled for movement in a similar direction, or the same may be operatively mounted for upward movement in an upward direction as illustrated in Figure 2 of the drawings, each of the targets being arranged for selective operation. In addition a target structure may be arranged for moving the target along a slightly inclined wire as shown at 34, or along a wire disposed

horizontally, such target being adapted to simulate the movement of an animal running along the ground.

In such construction a pair of relatively short posts are suitable upon which to attach the wire as indicated at 35. It is to be understood that the target 25 may be constructed of the bull's eye type as shown in Figure 2 of the drawings or the same may be placed in the simulation of a bird or animal and may be constructed of any suitable material, preferably of a non-fanciful type so that the marksman may inspect the target to determine the portion thereof upon which the shot strikes.

It is obvious that my invention is susceptible to various changes and modifications in construction without departing from the spirit or scope of the invention or appended claims, and I accordingly claim all such forms of the device to which I am entitled.

Having thus described my invention, what I claim as new is:

1. A target comprising a guide wire, supporting means at each end thereof, a target carrier movable along the wire, rollers mounted in the carrier and disposed at opposite sides of the wire, a resilient bumper disposed at one end of the carrier having a recess formed therein, and a trigger attached to the supporting means having one end adapted for positioning in the recess whereby to releasably secure the carrier against movement.

2. A target comprising a guide wire, supporting means at each end thereof, a target carrier movable along the wire, rollers mounted in the carrier and disposed at opposite sides of the wire, a resilient bumper disposed at one end of the carrier having a recess formed therein, spring means interposed between the supporting means and the carrier, a trigger attached to the supporting means having one end adapted for positioning in the recess whereby to releasably secure the carrier against movement and to retain the spring means in compressed position, and means for adjusting the trigger for regulating the tension of the spring means in its compressed position.

In testimony whereof I affix my signature.
